UNITED STATES PATENT OFFICE.

WILLIAM K. EDWARDS, OF BIG SPRING, TEXAS.

GATE-CLOSING DEVICE.

Application filed May 4, 1926. Serial No. 106,648.

This invention relates to gate closing devices, and in particular to such devices as are used for automatically effecting the closing movements of farm, and other gates of 5 the type which may be opened by the mere application of pressure to the gate.

An important object of the invention is to provide a device of the character referred to in which the gate, after being opened, is 10 adapted when released to swing closed by the action of gravity, the closing movement being checked or retarded suitably by a hydraulic or pneumatic fluid checking means.

The invention will be best understood from 15 the following detailed description, when considered in connection with the accompanying drawings, in which:

Fig. 1 is a view in front elevation, showing a gate equipped with the devices for effecting 20 its closing movement, said gate being shown in closed position;

Fig. 2 is a plan view illustrating the gate in open position;

Fig. 3 is a detail view, partly sectional, illustrating 25 the track and rollers for causing the gate to close;

Fig. 4 is an inverted plan view of the roller-supporting strip;

Fig. 5 is a plan view of the track;

Fig. 6 shows a cup or housing, in inverted 30 plan, for enclosing the rollers and track;

Fig. 7 illustrates the track in side elevation;

Fig. 8 is an elevation of the fluid checking 35 device;

Fig. 9 is a detail view, illustrating the arm for supporting the piston rod of the checking device from the gate center post; and

Fig. 10 is a sectional view of the piston.

40 The gate frame comprises a horizontal portion 2, herein shown as composed of two members, spaced, parallel, uprights, 3, 3, which may be connected by suitable elbows 4 with the horizontal members, and a center post 5, herein shown as connected by a T-coupling 6 with the horizontal members 2.

The outer uprights 3, and the gate center post 5 are suitably anchored to a base 8 whereby the gate frame is rendered rigid.

45 The gate, as herein shown, is composed of a plurality of slatted members 10, suitably spaced, and connected at their ends by vertical slats 12, the three lowermost strips or slats 10 of the gate being preferably connected by suitable braces 14. An elongated flat strip of metal 16, provided with upwardly

projecting perforated lugs 17, 18, is secured by bolts, rivets, or other fastenings along the lowermost slatted member 10 of the gate. Projecting downwardly from this strip 16, 60 at equal distances from the aperture 19 which receives the center post 5, the strip 16 is provided with the spaced lugs 20 which are perforated to form bearings for the spindles of rollers 22. The track 24 is formed by the upturned edge of a circular disk 25, which has a hub 26 fitting about the post 5, the hub being tapped to receive screws 27 which secure the disk 24 to the post. 65

The tracks are, as best shown in Fig. 7, inclined upwardly from two diametrically arranged depressions 28, 28, which latter receive the rollers 22 when the gate is in closed position. The gate is thus maintained in closed position until sufficient force is applied thereto to cause the rollers to pass out of the depressions 28 and mount the inclined portions of the track 24. Such inclined portions extend, each, from a depression 28, 90 degrees about the track on an up-grade, so that as the gate is swung from closed position, as shown in Fig. 1, to open position, as shown in Fig. 2, the rollers will cause it to rise slightly, and at the extreme open position of the gate the rollers rest upon the highest points of the tracks, so that when the gate is released gravity tends to cause the rollers to move down the inclined tracks for carrying the gate to closed position. 70 75 80 85

In order to protect and conceal the rollers and tracks, a cup or housing 29 of sheet metal, composed of a bottom portion 30 perforated at 31 to fit over the post 5, and having square apertures 32 to pass over the lugs 20 and rollers 24, is suitably fastened by rivets or the like to the under side of the strip 16. 90 95

An arm 34, having a semi-circular recess 35, and a like clamping member 36 provided with lugs 37 to receive bolts 38, is clamped to the post 5 immediately above the gate. As shown in Fig. 2, this arm projects about midway between the gate frame and the position occupied by the gate when the latter is fully opened. The outer end of the arm is perforated to receive a pin 40 connecting the arm with the piston rod 41, the latter having its outer extremity forked at 42, to receive said arm. The piston rod is herein shown as having a reduced and threaded end 43, which latter enters perforations in a plate 44, metal cup 45, and cupped washer 46, con-

stituting a piston. Said parts of the piston are secured to the reduced end of the rod 41 by a nut 47. The metal cup 45 is shown as provided with a plurality of perforations 58 to receive guide pins 49, which project inwardly from a spring 50. This spring has a natural expansion tendency, and yieldingly maintains the washer 46 against the walls of a cylinder 52 within which the piston plays. Said cylinder is provided at its inner end with a perforated projection 53, which passes over a pin 54 projecting upward from a suitable bracket 55 carried by the upper slat of the gate. It will thus be seen that the fluid checking device comprising the piston, rod and cylinder, is pivotally connected at 40 and 54 to the arm 34, and the gate. By such construction, when the gate is moved from closed to open position the cylinder is carried from the position shown in Fig. 1 to that shown in Fig. 2, and in swinging about the pivot point 40 as a center, movement of the cylinder causes the piston to travel first inwardly, and after passing the center 40 to travel outwardly. When the gate stands in the position shown in Fig. 2, as it will after having been moved a distance equal to 90 degrees, in passing from fully closed to fully open position, the rollers 22 will have traveled from the lowest to the highest points on the tracks 24. Upon release of the gate it will start to close by the action of gravity, the rollers moving down on the tracks. This closing movement will, however, be checked because of the resistance to movement of the gate offered by compression of the air in the cylinder 52, as the latter travels relatively to the piston, during the swinging movement of the gate. The gate will thus be retarded in its closing action, and will move slowly from open to closed position, such retardation being sufficient to enable the driver of an automobile, or other vehicle, or a

pedestrian who has passed through the gate, sufficient time to clear the gate prior to the latter's movement toward closed position. 45

The device is especially efficient in that the self-closing elements, comprised in the inclined tracks 24, 24, and rollers 22, 22, are cooperatively related to the pneumatic checking device which holds the gate back, and prevents it from instantly swinging about its axis from fully open toward a closed position, when released. The advantage of thus holding back the gate and slowing its closing movement is especially noticeable where, for example, a motor vehicle is so driven as to force the gate open, on the right hand side of the road, and after passing through will be enabled to clear the gate before the latter has moved far enough in its return movement, to engage the vehicle. 55 60

Having thus described my invention, what I desire to secure by Letters Patent is:—

In a gate, the combination of a frame having a vertical post, supporting means comprising a disk having upturned flanges formed as inclined tracks, depressions at the bases of the tracks, arranged substantially diametrically opposite each other, a gate mounted to swing from open to closed position about said post as a center, spaced lugs projecting below said gate, anti-friction rollers between said lugs having axles with bearings in said lugs, said rollers arranged at diametrically opposite points and resting upon said inclined ways, and a housing having its bottom portion centrally perforated to pass over the post and provided with spaced apertures to pass over said lugs and arranged with an annular depending portion to protect and conceal said rollers. 70 75 80

In testimony whereof I have hereunto set my hand this 28th day of April A. D. 1926.

WILLIAM K. EDWARDS.
